UNITED STATES PATENT OFFICE.

CHARLES T. BRENNAN, OF WATERBURY, CONNECTICUT, ASSIGNOR TO THE E. J. MANVILLE MACHINE COMPANY, OF WATERBURY, CONNECTICUT, A CORPORATION OF CONNECTICUT.

MECHANISM FOR FEEDING METAL BLANKS.

Application filed December 19, 1924. Serial No. 756,903.

To all whom it may concern:

Be it known that I, CHARLES T. BRENNAN, a citizen of the United States, residing at Waterbury, in the county of New Haven and State of Connecticut, have invented a new and useful Improvement in Mechanism for Feeding Metal Blanks, of which the following is a specification.

This invention relates to the feed mechanisms which are provided for metal heading, re-heading, trimming, thread rolling, knurling, slotting and other machines in which metal blanks are automatically fed from a promiscuous mass in a hopper to a track down which the blanks travel by gravity to means which transfer them one at a time to the operating tools. Frequently these machines are called upon to act upon blanks which have cross sectional shapes that are other than circular. For example, the shanks of the blanks may be square, oblong, oval, or flattened on one or more sides, and then it is necessary to feed these blanks in such a relation to the transfer mechanism that they will be presented correctly to the operating tools. For instance, an oblong or flattened blank must be carried between the punch and die of a heading or re-heading machine in such position that it will conform to the openings therein, otherwise not only will the stock be destroyed, but the tools be damaged when they are brought into action for shaping the stock.

The object of the present invention is to provide simple means applicable to the usual feeds for such machines which will enable blanks having irregular cross sections to be automatically fed from a hopper down a track and all be correctly presented to the operating tools.

This object is attained in the embodiment of the invention illustrated by providing a track having a way that at the upper or hopper end is as wide as the largest diameter of the blanks to be fed thereto and that at the lower or delivery end is only as wide as the smallest diameter of the blanks, and arranging at the locality where the track path converges from the widest space to the narrowest space, a whirl with its periphery extending into the way in such manner that it will engage the blanks and turn them so that they will enter the narrow path and not jam

and choke the track where it is reduced in width.

In the accompanying drawings Fig. 1 shows a side elevation of a blank feed that embodies the invention. Fig. 2 is a plan of the track and the blank positioning whirl. Fig. 3 is a section on the plane indicated by the dotted line 3—3 on Fig. 1. Fig. 4 shows a side view of a blank from which an automatic tire valve stem is to be formed and which is to be reheaded, this blank being chosen to illustrate the action and utility of the present invention. Fig. 5 is a section of the valve blank on the plane 5—5 on Fig. 4. Fig. 6 illustrates the manner in which such valve blanks, while being fed, are automatically straightened according to this invention.

In the views the track plates 1 are shown as fastened by bracket 2 to the front wall of a blank holding hopper 3 which hopper may be of any common type. The lower ends of the track plates may be supported by a suitable bracket 4. The top edges of the plates are inclined at the necessary angle to permit the blanks hanging by their heads with their stems depending into the path between the plates to slide by gravity from the upper end to the delivery end. The track plates are so formed and spaced apart that the opening 5 between their upper sections will be as wide as the largest diameter of the stems of the blanks to be fed, while the opening 6 between the lower sections of the track plates is narrowed so as to be only as wide as the smallest diameter of the stems of the blanks, the path between the plates converging at the locality 7 from the greater width to the lesser width. In the construction illustrated this is accomplished by having the inner face of one track plate in a single plane and having the inner face of the other plate extending in two planes and this may be attained by making one plate of uniform thickness and the other of two different thicknesses.

Supported by a bracket 8 attached to one track plate adjacent to the locality of convergence of the path between the plates is a spindle 9 that at its upper end has a roll 10 and at its lower end a pulley 11. The roll 10 is of such diameter and is so located that its periphery will extend into the wider

space but not into the narrower space between the plates. In the form shown the bracket has an arm 12 carrying pulleys 13. A driving belt may be led from any suitable rotating member of the machine to which the feed is applied around the pulleys for the purpose of rotating the wheel 10.

With the arrangement illustrated blanks, such as the tire valve blank 14, the stem 15 of which is flat on two sides, may be fed from the hopper to the track by the commonly employed mechanism for feeding blanks, and it makes no difference which way the stems of the blanks are turned in the upper part of the track path for the space there is sufficiently wide to receive the blanks with their largest diameter cross-wise. When such blanks of irregular diameter during their downward travel reach the converging section of the path between the track plates if they are not in such position as to pass into the narrower section of the path they are engaged by the whirl and turned so that they will enter the narrower section of the path, as illustrated in Fig. 6. When the blanks are turned in the manner suggested they will all be delivered from the lower end of the track in the same relation so that they can be transferred correctly to the punch and die or other tools by

which they are to be acted upon. If such blanks as mentioned for example, are to be re-headed and they were not delivered from the track all in the same way they would not be transferred to between the 35 punch and die in the necessary relation to enter the die, consequently they would be jammed out of shape and the tools be broken when the punch came up. By the employment of the means herein described the correct feed of the blanks is ensured. 40

The invention claimed is:

A mechanism for feeding headed metal blanks that have irregular shaped stems, comprising inclined track plates spaced 45 apart to support the blanks by their heads with the stems extending down between the plates, the upper section of the path between the plates being wider than the lower section of the path, and a whirl with its 50 periphery extending into the path adjacent to the point of convergence from the wider to the narrower section, said whirl being adapted to engage and turn the stems of those blanks which arrive at this locality in 55 such positions that they will not enter the narrower section of the path, so that they will enter the narrower section.

CHARLES T. BRENNAN.
